MOP HANDLE SUPPORT

Robert C. Teare, Evanston, Ill., assignor to
O-Cedar Corp'n, Chicago, Ill., a corporation of
Illinois

Application September 21, 1935, Serial No. 41,606

2 Claims. (Cl. 306—19)

This invention relates to a mop handle support and more particularly to improved means for connecting a mop handle to the mop frame or head.

5 An object of the invention is to provide a mop handle coupling device of simpler construction than heretofore used and possessing new advantages.

10 A further object is to provide such a coupling device equipped with means for confining portions of the mop head against lateral disengagement. Other specific objects and advantages will appear as the specification proceeds.

15 The invention is illustrated in a preferred embodiment, by the accompanying drawing, in which—

20 Fig. 1 is a plan view of a mop head equipped with a coupling device embodying my invention; Fig. 2, a side view in elevation, the mop head being sectioned as indicated by line 2 of Fig. 1; Fig. 3, a sectional detail view, the section being taken as indicated at line 3 of Fig. 2; and Fig. 4, a broken plan view of the joint formed by the free end portions of the mop head, the view being taken as indicated at line 4 of Fig. 3.

25 The mop head or frame may be of any suitable construction. The specific form of mop head shown is given merely for the purpose of illustration.

30 In the specific illustration given, the wire frame 10 which forms the mop head is provided with free end portions 11 and 12 which are brought together to form a hinge shank. The extremities 35 of the portions 11 and 12 are preferably swaged or otherwise enlarged to form an enlarged overlapping joint 13.

35 The coupling member 14 may be of any suitable construction and material. I prefer to form the coupling 14 of a metal blank. The blank is turned upon itself and then shaped on suitable tools to provide at one end a cylindrical sleeve 15 adapted to receive the hinge shank of the head 10 and to provide also a rearwardly extending socket portion 16 adapted to receive the handle of a mop. The socket portion 16 may be provided with usual threaded portions 17 adapted to interlockingly engage threads on the end of the mop handle. The upper and lower 45 halves which form the socket 16 are preferably locked together by a thimble 18 which engages the rearmost end of the metal piece 14, the thimble being hollow to permit the handle to extend therethrough.

50 In order to brace the cylindrical portion 15

and to maintain it in tight frictional contact with the shank of the head, I prefer to form side flanges or webs 19 between the socket portion 16 and the cylindrical bearing 15. At the same time, I provide a longitudinally extending rib 5 20 from the socket portion 16 on one side about the bend of the metal and to the socket portion 16 on the other side. In the illustration given, the rib merges with the socket portion 16 on each side of the metal. With this construction, 10 the rib and the socket portion provide a continuous vertical reinforcement for the metal piece from end to end. The socket 20, in addition to the advantages mentioned, provides an enlarged chamber 20^a adapted to freely receive 15 the enlarged joint 13 formed by the extremities of the end portions 11 and 12 of head 10. The chamber 20^a enables the metal piece 14 to rock freely on the hinge shank but prevents lateral movement of the free end portions 11 and 12. 20 If desired, the rib 20 may be omitted, the ends of the portions 11 and 12 not being enlarged.

25 In the preferred practice heretofore, it has been customary to form the metal piece 14 of two parts and to secure them together by bolts and more commonly by a bolt extending through the central portion of the coupling member just ahead of the socket. By forming the metal piece from one part, I am able to dispense with the bolt and to utilize the space formerly occupied 30 by the bolt for forming the vertical rib with its enlargement for receiving the wire extremities.

35 The new coupling member can be more readily assembled than those heretofore used. After the enlarged ends have been brought together to 40 form the joint 13, the metal piece 14 which has been only partially bent back upon itself, is drawn quickly into position with the cylindrical portion 15 receiving the shank of the head and with the chamber 20^a receiving the joint 13. The 45 rearmost portions of the metal piece 14 are then brought together and the thimble 18 readily inserted to lock the two parts permanently in the position shown in Figs. 2 and 3. The entire head and coupling device are thus permanently assembled, the free end portions of the head being securely locked within the member 14 while at the same time not hindering the pivotal movement of the coupling device 14.

50 The foregoing detailed description has been given for clearness of understanding only, and no unnecessary limitations should be understood therefrom, but the appended claims should be construed as broadly as permissible, in view of the prior art.

I claim:

1. In a mop handle support, a mop head comprising a flexible wire frame provided with free end portions substantially axially aligned and provided with enlarged terminals, a handle coupling formed of one piece bent back upon itself to provide a handle-receiving socket at one end, and a transverse bearing at the other end, said coupling being provided with a rib extending from the socket and surrounding the bearing, said rib receiving said enlarged terminals and locking them within said coupling.
2. In a mop handle support comprising a

handle coupling formed of one piece bent back upon itself to provide a handle-receiving socket at one end, a transverse bearing at the other end, and a rib extending from the socket and surrounding the bearing, a flexible wire frame provided with free end portions substantially axially aligned and each provided with a flattened terminal together forming an enlarged overlapping joint, said enlarged overlapping joint being received within said rib and locked thereby within 10 said coupling. 5

ROBERT C. TEARE.
